UNITED STATES PATENT OFFICE.

MARTIN C. SCHWAB, OF BALTIMORE, MARYLAND.

CONVEYER.

SPECIFICATION forming part of Letters Patent No. 764,012, dated July 5, 1904.

Application filed September 30, 1903. Serial No. 175,135. (No model.)

To all whom it may concern:

Be it known that I, MARTIN C. SCHWAB, a citizen of the United States, residing at Baltimore, State of Maryland, have invented certain new and useful Improvements in Conveyers, of which the following is a specification.

This invention relates to improvements in spiral conveyers adapted for use in buildings or stores for conveying packages by gravity from the various floors downward.

The object of the invention is to provide improvements in this class of conveyers, as hereinafter set forth, and particularly pointed out in the appended claims.

15 The invention is illustrated in the accompanying drawings, in which—

Figure 1 is a vertical sectional view of a conveyer constructed according to my invention extending through several floors of a building. Figs. 2, 3, 4, and 5 are horizontal sectional views taken approximately on the lines 2 2, 3 3, 4 4, and 5 5, respectively, of Fig. 1.

In the accompanying drawings the invention is illustrated as installed in a building having four floors. The lower or ground floor A represents the shipping department, and the upper floors are designated, respectively, B, C, and D. It is to be understood that this 30 conveyer may be installed in a building having any number of floors and may be located in any convenient place in a building consistent with the architectural plan thereof.

In the present instance the conveyer comprises a plural number of tubes concentrically arranged one within the other. The outer tube or shell *a* extends from the lower floor or shipping department to the next floor above. A spiral chute *a'* is secured within this shell 40 *a*, and said chute extends from the second floor B down to the shipping department. An opening *a''* in the shell *a* and near the upper end of the chute gives access or communication to said chute, and a discharge-opening *a'''* is provided in said shell at its lower end, through which the packages pass to discharge onto a platform A' in the shipping department. It will thus be seen that a package 45 upon being placed on the chute *a'* at the second floor B will be conveyed down the outer

spiral around the shell *a* and discharge through the opening *a'''*. A tube or shell *b* extends vertically through the outer shell *a*, and said tube is longer or higher than the shell *a* and extends to the third floor C, being the floor 55 next above that at which the tube *a* terminates. This second tube or shell *b* is also provided with a spiral chute *b'*, which latter extends from the third floor C down to the lower floor or shipping department. An opening *b''* is provided in the shell at the third floor C and communicates with the chute *b'* and permits the deposition of packages on said chute. The second chute *b'* at its lower end passes through an opening in the shell *b* and also extends through the outer shell *a* and terminates on the platform A'. It will be apparent that a package deposited on the second chute *b'* will not interfere with anything on the first chute and will be conveyed to the lower floor 70 or shipping department A and deposited on the platform A'. An inner tube or third shell *c* extends vertically through the second shell *b*, and its upper end terminates above the fourth floor D. This tube is also provided with a spiral 75 chute *c'*, which extends from the fourth floor down to the shipping department A, where its lower end terminates. In the present instance a tube or core *E* extends vertically through the center of the shell *c*, and the inner chute *c'* winds spirally around said core. An opening *c''* is provided in the shell *c* at the fourth floor D, through which packages may be placed on said chute *c'*. At its lower end the chute *c'* passes through the wall of the shell *c* 80 and also through the shells *b* and *a*, and said chute *c'*, like the chutes *a'* and *b'*, terminates on the same platform A' in the shipping department. It will thus be seen that the several independent spiral chutes from the various floors all terminate at the same platform A'. The exterior surfaces of the shells on the several floors are preferably inclosed in plaster or other suitable jacket *c*.

The operation is obvious.

It is obvious that the invention is not limited to a device for conveying packages, but may be employed to convey anything from an upper to a lower floor.

Having thus fully described my invention,

what I claim as new, and desire to secure by Letters Patent, is—

1. A conveyer for transmitting packages from one floor to another of a building, comprising a plurality of spirals, one concentric with respect to the other, and one end of each spiral starting from a different floor and the other ends of all of said spirals terminating at the same floor. 35
- 10 2. A conveyer for transmitting packages from one floor to another of a building, comprising a plurality of spirals of different diameters one around the other, one of the ends of each of said spirals starting from a different floor and the other ends of all of said spirals terminating at the same floor. 40
- 15 3. A conveyer for transmitting packages from one floor to another of a building, comprising a plurality of spirals concentrically arranged one within another and each of the inner spirals extending from a higher point than the outer adjoining one next surrounding it. 45
- 20 4. A conveyer for transmitting packages from one floor to another of a building comprising a plurality of spirals of different diameters, the spiral having the smallest diameter connecting the highest and lowest floors that are in communication with the conveyer, 50
- 25 and the spiral having the largest diameter connecting the lower floors that are in communication with the conveyer. 55
- 30 5. A conveyer for transmitting packages from one floor to another of a building, comprising a plurality of tubes or shells concentrically arranged, the upper ends of said tubes each starting from a different floor and the lower ends of all of said tubes terminating at the same floor, and a spiral chute in the concentric space formed by each of said tubes. 60
- 35 6. A conveyer for transmitting packages from one floor to another of a building, comprising a plurality of tubes of different diameters and different lengths and one within the other, and a spiral chute in each of said tubes. 45
- 40 7. A conveyer for transmitting packages from one floor to another of a building, comprising a plurality of tubes of different diameters concentrically one within the other, a spiral chute in the space between each two adjoining tubes and all of said chutes discharging through the wall of the tube of the largest diameter. 50
- 45 8. A gravity-conveyer for establishing communication between the various floors of a building having a plurality of spiral chutes of different diameters and lengths and each of said spirals occupying a different circular plane. 55

In testimony whereof I affix my signature in the presence of two witnesses.

MARTIN C. SCHWAB.
